United States Patent Office.

RALPH C. WHITEHOUSE, OF BOOTHBAY, MAINE.

Letters Patent No. 77,426, dated April 28, 1868.

IMPROVEMENT IN CLEVIS.

The Schedule referred to in these Letters Patent and making part of the same.

TO ALL WHOM IT MAY CONCERN:

Be it known that I, RALPH C. WHITEHOUSE, of Boothbay, in the county of Lincoln, and State of Maine, have invented a new and useful Improved Clevis; and I hereby declare the following to be a full, clear, and exact description thereof, which will enable others to make and use my invention, reference being had to the accompanying drawings, forming part of this specification, in which—

Figure 1 is a side view of my invention.

Figure 2, a section of the same.

The object of my invention is to provide a simple and easy means of fastening and unfastening cattle to and from carts and sleds.

To perform this operation when the common clevis is used, it is necessary to pass between the cattle, and this is always attended with inconvenience and loss of time, and not unfrequently with danger. To avoid this, I make my clevis strictly automatic in regard to attaching the oxen to the cart or sled, for it is only required to pass the tongue of the vehicle through the ring of the yoke, and back the cattle.

The drawings will be easily understood. *a* is the iron funnel or box-containing the clevis, which passes over the cart-tongue. *b*, the clevis, attached at the upper end by a pivot, *c*, and passing through the box *a*, having also a lip, *d*, resting on the edge of the aperture in the clevis-box, to protect it from dropping lower than necessary. This is more distinctly shown in section in fig. 2, the dotted lines showing the swinging motion of the clevis. When the clevis is in the position shown in fig. 1, the strain of the drawing cattle does not come on the pin or pivot *c*, but upon the shoulder *d* of the box, (see fig. 2,) thus adding much to its strength and durability. The hold-back is seen at *e*, and a section of the ring is shown in fig. 2, in its place between the clevis and hold-back. Over the upper end of the clevis is placed a spiral spring, *f*, which passes through a hole in the tongue of the cart, and aids in keeping the clevis in position.

When the cattle are to be detached, a slight pressure on the bottom of the clevis will push it up, so as to allow the ring to slip off easily.

It is obvious the device would operate automatically without the intervention of the helix *f*, this simply adding security, and preventing the clevis from jolting up or down. *g* shows the loop to which the leaders are attached as common.

What I claim as my invention, and desire to secure by Letters Patent, is—

The combination of the clevis-box *a*, having its pivoted clevis *b*, hold-back *e*, either with or without the helix *f*, and to be attached as and for the purposes set forth.

RALPH C. WHITEHOUSE.
